(57) **CLAIM**

The ornamental design for a combined waste bag holder and cart, as shown and described.

DESCRIPTION

FIG. 1 is a front, side perspective view showing the front and right side of the combined waste bag holder and cart in an extended position;

FIG. 2 is a right side view, the left side being a mirror image thereof;

FIG. 3 is an elevational front view thereof;

FIG. 4 is an elevational rear view thereof;

FIG. 5 is a top plan view thereof;

FIG. 6 is a bottom plan view thereof;

FIG. 7 is a rear perspective view thereof;

FIG. 8 is a front perspective view showing the cart in a folded position; and,

FIG. 9 is a rear perspective view showing the cart in a folded position.
